UNITED STATES PATENT OFFICE.

R. J. HAMILTON, OF CHICAGO, ILLINOIS.

IMPROVEMENT IN JOURNAL-BOXES FOR CAR-WHEELS.

Specification forming part of Letters Patent No. 37,814, dated March 3, 1863.

To all whom it may concern:

Be it known that I, R. J. HAMILTON, of the city of Chicago and county of Cook, in the State of Illinois, have invented a new and useful Improvement in Oil or Journal Boxes for Car-Wheels; and I hereby declare that the following is a full, clear, and exact description thereof, reference being had to the accompanying drawings and letters and figures marked thereon, which form a part of this specification.

In the aforesaid drawings, Figure 1 represents an outside end view of the journal-box, which is of any of the known forms. Fig. 2 represents a side view showing a section at the line x . Fig. 3 shows a transverse or cross-sectional view at the line x' , and Fig. 4 shows a similar sectional view at the line x'' .

The same letters denote corresponding parts or portions of my invention in the several figures.

The views shown in Figs. 1, 3, and 4 are taken from the end nearest to the wheel marked W in Fig. 2.

The nature of my invention consists in a device or devices to economize or prevent the waste of oil used in lubricating the journals and the supports thereof of the axles of car-wheels.

To enable those skilled in the art to understand and construct my invention, I will proceed to describe it with particularity.

B represents the axis of the wheels, D and E the supports of the journal, and H the chamber to contain the oil. d , whose position is shown in Fig. 3 by the dotted lines d d d , represents a fixed stationary collar, which fits about, and upon which rests, the axis or journal.

A represents a similar movable collar, which is adjusted to the journal by means of the spring a beneath it, and also to the support marked S in Fig. 2.

C represents a washer, of leather or other suitable material, which is fitted about the

journal within a circular groove made in the supports D E. This washer is cut asunder at b diagonally or obliquely, so that each part has a sharp edge or lip to facilitate the ends passing by each other upon pressure applied. Beneath C is placed the spring c , which operates in a similar manner to the spring a .

The nature of my invention consists in having the adjustable collar A placed upon the spring a , so that when the bearings and supports become worn by use and the journal recedes from the fixed collar d , the spring a will cause the adjustable collar A to follow up and continually press against the journal and the support S, thereby preventing the oil which passes or runs over the fixed collar d to escape.

My invention consists, further, in having the diagonal or oblique cut made in the washer C, (shown at b), and in having the spring c placed beneath, as shown in Figs. 1, 2, and 3, so that when the bearings and supports become worn as aforesaid and the journal recedes from below the spring c will press the washer up against said journal, making the washer assume the position and form as represented by the dotted lines e e in Fig. 4, the edge b passing by to b' , thus preventing the ingress of sand and dust into the box.

f and g are openings through d and E to allow any oil that may by any chance escape to pass back into the oil-chamber H.

I claim as my invention—

The combination and arrangement of the adjustable collar A and the washer C when cut as described, and both are operated upon and used with the springs a and c , or their equivalents, and the openings g and f , when all are arranged and operating substantially as and for the purposes delineated and set forth.

R. J. HAMILTON.
